SEWING MACHINE

Ramon Casas Robert, Geneva, Switzerland, assignor to Mefina S. A., Binningen, Switzerland

Application March 31, 1949, Serial No. 1,736
In Switzerland December 20, 1948

Term of patent 14 years

(Cl. D70—2)

To all whom it may concern:

Be it known that I, Ramon Casas Robert, a citizen of Spain and resident of Geneva, Switzerland, have invented a new, original, and ornamental Design for a Sewing Machine, of which the following is a specification, reference being had to the accompanying drawing, forming part thereof.

Fig. 1 is a front perspective view of a sewing machine, showing my new design,

Fig. 2 is a top plan view thereof,

Fig. 3 is a rear perspective view,

Fig. 4 is a perspective view showing the side carrying the fly-wheel,

Fig. 5 is a perspective view showing the opposite side, and

Fig. 6 is another front perspective view of the sewing machine shown in Fig. 1.

The essential features of my design reside in the portions shown in solid lines.

I claim:

The ornamental design for a sewing machine, as shown and described.

RAMON CASAS ROBERT.
